BOWLING BALL RACK

Ralph Grimes, 207 W. Plum St.,
Georgetown, Ohio 45121

Filed June 2, 1966, Ser. No. 2,520

Term of patent 14 years

(Cl. D34—5)

FIG. 2

FIG. 3

FIG. 4

FIG. 5

FIG. 6

FIG. 7

FIG. 8

FIG. 1 is a plan view of a bowling ball rack showing my design;

FIG. 2 is a front elevational view thereof;

FIG. 3 is an end elevational view thereof;

FIG. 4 is a rear elevational view thereof;

FIG. 5 is a sectional view taken on the line 5—5 in FIG. 1;

FIG. 6 is a sectional view taken on the line 6—6 in FIG. 1;

FIG. 7 is a sectional view taken on the line 7—7 in FIG. 1; and

FIG. 8 is a sectional view taken on the line 8—8 in FIG. 7.

I claim:

The ornamental design for a bowling ball rack, as shown.
